UNITED STATES PATENT OFFICE.

EPHRAIEM CHAQUETTE, OF NEW ROCHELLE, NEW YORK.

LAND-RECLAIMING DOCK.

SPECIFICATION forming part of Letters Patent No. 702,627, dated June 17, 1902.

Application filed October 5, 1901. Serial No. 77,647. (No model.)

To all whom it may concern:

Be it known that I, EPHRAIEM CHAQUETTE, a citizen of the United States, and a resident of New Rochelle, county of Westchester, 5 State of New York, (whose post-office address is 63 Mechanic street, New Rochelle,) have invented certain new and useful Improvements in Land-Reclaiming Docks, of which the following is a specification.

- 10 The object of my invention is to provide a floatable apparatus or dock which can be moored or anchored conveniently near the marsh low land, or other locality to be reclaimed, and which shall be adapted to receive 15 from scows or other receptacles the mud and other materials dredged up from bays, rivers, and other bodies of water and to deposit the same upon the locality to be reclaimed.
- 20 One application of my invention is shown in the accompanying drawings, in which— Figure 1 is an end elevation. Fig. 2 is a cross-section. Fig. 3 is a top plan. Fig. 4 is a longitudinal section. Fig. 5 is a detail showing the bottom of the receiving-vats.

Same letters indicate similar parts in the different figures.

A is the frame or body of the dock, containing the waterway B. This dock is made of 30 substantial material and of sufficient size to admit a scow such as is generally employed in connection with harbor-dredges for receiving the mud and other substances raised by the dredge. This dock is designed to be 35 moored as near as possible to the shore adjacent to the land to be reclaimed, but is to be sunk to such depth that there will be water enough in the waterway B to float the mud-scows or other vessels from which filling material is to be received. This will ordinarily 40 require a depth of some fifteen feet of water in the waterway B. That part of the dock which is immediately below the waterway is divided into a convenient number of vats or 45 receiving-troughs C, the sides of which taper inwardly downward to form a trough, which said trough also inclines downwardly toward the pumping side of the dock. By means of this construction the contents of the vats are 50 by their own weight constantly impelled toward the pumps. The pumping portion of the dock is provided with an engine D, which

drives a dynamo-machine E, which in turn operates the motor F, from which the power necessary to drive the pumps is delivered. 55 These devices may be of any desired and convenient construction and are to be located at such places in the dock as is found most convenient.

A series of rotary pumps G G is provided, 60 one for each of the vats C, from which it sucks out the material deposited by the scow. Each of these pumps has a discharge-pipe f f, through which the material drawn from the vat is forced. These several pipes are so arranged as to combine at some convenient locality, preferably at the top of or above the dock, into a single discharge-pipe (not shown) which leads to the shore and has its discharge end located above the territory to be reclaimed. It is of course to be understood 70 that the position of the outer end of the discharge-pipe will be changed from time to time as the swamp, low land, or other territory to be reclaimed is filled up by the material discharged from said pipe.

The various pumps G G are preferably operated in succession instead of simultaneously, as thereby the power required by the engine D and motor F will only be that required for 80 a single pump. There need be no loss of time by this successive operation, because the interval between the arrival of successive scows will be sufficient to empty all the vats one at a time. To accomplish this operation of the 85 pumps G in sequence, they are arranged and mounted as follows: A driving-shaft a, journaled in suitable bearings secured upon the framework of the dock, runs along the line of pumps and carries a number of gear-wheels 90 b b, which mesh, respectively, with the pump-gear c c. The gears b b, however, are loose upon the shaft a, each being accompanied by a clutch d, which is splined upon the shaft a and which when brought in connection with 95 its corresponding gear turns the same and communicates the rotation of the shaft a to the pump which it is desired to operate. The selection of the pump to be operated is made by the engineer in charge, the pump being 100 shut off as soon as its vat is empty and a new pump started. Each pump is also provided with a valve e, by which communication with a vat is opened or closed.

Rotation is communicated to the shaft a from the motor F as follows: The motor-shaft a' , journaled in suitable bearings, carries a gear h , which meshes with an intermediate gear j , mounted upon a secondary shaft a'' , journaled in the framework and carrying a gear l , which meshes with the gear m , keyed to the shaft a . It will thus be seen that the shaft a is in constant rotation during the operation of the motor F, but that this rotation is communicated to the pumps only when one or more of the clutches d takes up its corresponding transmitting-gear.

The rotary pumps G G are of ordinary and usual construction and provided with a suction-pipe f' , leading from the bottom of the trough C C. To aid the suction of the mud and other heavy material deposited in the troughs, I provide in the bottom of each vat the agitating and feeding chain p , which is kept in constant motion over the sprockets s , one an idle sprocket at the end of the trough and the other preferably mounted inside the suction-pipe on the shaft a'' , Fig. 3. This shaft carries the splined clutches d' and is turned positively by connection (not shown) by the pump-gear c .

The operation of my land-reclaiming dock is as follows: A loaded scow is drawn into the waterway B, so that its discharge-gates are immediately above the receiving-vats C. These gates are then tripped in the ordinary way and the contents of the scow deposited in the vats. The scow is then withdrawn from the waterway and is towed back to the dredge or other source of filling material. One of the pumps G is then set in operation by bringing its corresponding clutch d into contact with its transmitting-gear and continued in operation, sucking out the material from the bottom of the vat through the pipe

f' and forcing it through the pipe f into the common discharge-pipe, by which it is carried and from whence it is delivered to the locality to be reclaimed. As soon as the solid contents of one vat have been withdrawn the operation of its corresponding pump is stopped and a new pump started by moving the proper clutch. This goes on until all the pumps have operated to empty their respective vats and the dock is ready to receive another scow-load.

The advantages of my apparatus will, I think, be readily understood, as by it I am not only able permanently to remove the material raised by harbor, river, or other dredges permanently from the water, but I utilize this material in making new land.

I claim—

1. A land-reclaiming dock adapted to be moored near the locality to be reclaimed and provided with a waterway which allows the passage of scows or other vessels through the same, receiving channels or vats arranged transversely thereunder and inclined toward the pump side, and suitable pumping and conveying apparatus by which the dredged material received from said scows or other vessels may be conveyed to or deposited on said locality substantially as described.

2. A land-reclaiming dock provided with a suitable waterway, receiving-vats thereunder, pumping and conveying apparatus, and a stirring and agitating chain at the bottom of each vat and adapted to feed the dredged material to the pump, substantially as described.

EPHRAIEM CHAQUETTE.
